METHOD AND APPARATUS FOR WORKING
CYLINDRICAL SHEET METAL ARTICLES
HAVING CLOSED BOTTOMS

Carl L. Clark, Warren, Ohio

Application August 6, 1936, Serial No. 94,598

3 Claims. (Cl. 153—29)

My invention relates to a method of and apparatus for rolling-in or reducing the diameter of the open end portion of drawn or welded cylindrical metallic shells having closed bottoms and outward turned annular flanges at the open ends thereof, and is of particular application for reducing the diameter of the open end portion of cylindrical metallic washing machine tubs having closed bottoms and curled flanges at the reduced open end portions and being drawn from a single piece or blank of sheet metal, or having the bottom portion welded to the cylindrical sheet metal portion.

Present methods for accomplishing the reduction of the diameter of the open end portions of shells as described above consist either of spinning, which is a slow operation, or by means of a roll contacting the outside face of the side wall of a shell and moving radially toward the axis thereof. Both of these methods require that an appreciable width of stock at the open end of the shell extend beyond the rolled-in portion to prevent buckling or wrinkling of the flange. This metal must be trimmed off and discarded thereby causing a substantial loss in material.

Further, present methods are inadequate and slow for reducing the diameter of the open end portions of washing machine tubs designed for household use which are streamlined to blend with the curved contour of the lids used to close the open or top end of the tubs. Such closed-in tubs are reduced in diameter at the open end as much as two inches and more.

Accordingly it is a principal object of my present invention to provide an improved and inexpensive method for accomplishing a substantial reduction in the diameter of the open end portion of cylindrical metallic shells having closed bottoms and outward turned flanges at the open ends and being drawn from a single blank of sheet metal, or being of welded construction as described in paragraph one.

It is a further object of my present invention to provide an improved apparatus for reducing the diameter of the open end portion of shells described in the preceding paragraph.

Also it is a further object of my present invention to effect economy in the amount of material required to roll in or reduce the open end portions as above described. This economy is effected because no metal is required in the side wall of the shell at the open end beyond the rolled-in portion because as the rolling-in operation progresses the margin of the shell is gripped

between rolls engaging both faces of the shell thereby preventing wrinkles forming.

The improved method of my present invention may be stated as including the steps of clamping the bottom portion of a cylindrical metallic shell having a closed bottom and outward turned annular flange at the open end, thereby holding the shell against axial and radial movement, holding the shell in alignment on a roll spaced from the flanged portion, said roll being held against axial and transverse movement, clamping the flanged end of the shell between two rolls one of which is radially yieldable with respect to the shell, and working the metal in and adjacent to said flange by rotating the rolls and moving the rolls engaging the flanged end portion radially toward the axis of the shell thereby reducing the diameter of the open end portion of the shell.

The improved apparatus of my present invention includes a chuck to hold the shell against axial and radial movement, a supporting roll held against axial and transverse movement and arranged to contact the inside face of the shell on a line spaced from the open end of the shell, a pair of rolls to grip the flanged end of the shell therebetween, means to move one of said rolls, designated a forming roll, toward and away from the shell, means to rotate the three rolls, yielding means to urge the second of said pair of rolls, designated a pressure roll, against the shell and to guide the movement of said pressure roll radially with respect to the shell, said pair of rolls after gripping the shell to move in unison radially with respect to said shell to reduce the diameter of the open end portion thereof.

The above and other objects, features and advantages of my invention will be apparent as the following description proceeds, reference being had to the accompanying drawing which shows, by way of example, preferred embodiments of the improved apparatus. Description of the drawing follows, in which

Fig. 1 is a partial side view of a conventional type rolling machine adapted for rolling open ends of cylindrical shells, showing the machine in vertical section;

Fig. 2 is a cross-sectional view taken along line 2—2 of Fig. 1;

Fig. 3 is a cross-sectional view taken along the line 3—3 of Fig. 2;

Fig. 4 is a partial plan view showing the gears in Fig. 3;

Fig. 5 is a partial cross-sectional view of the

rolls in Fig. 1 showing the position of the rolls at the start of the rolling operation;

Fig. 6 is a view similar to Fig. 5 showing a variation in the top roll 21, the modification of the roll comprising a groove designed to receive an outward turned flange on the shell 38.

Fig. 1 shows the cylindrical shell 38 with the open end closed in. Shell 38 is located in position by means of plate 39 and pusher plate 40 which hold the shell firmly in place and rotate therewith. Roll 22 is mounted to rotate freely on sleeve 41 which is in turn mounted on shaft 20 and rotates therewith. The contour of the roll 22 determines the contour of the rolled in end of the shell 38. Roll 21 is mounted on shaft 19 and rotates with it, and is raised for removal of the finished shell and for reloading and is caused to feed downward and upward by a drive mechanism not shown which is conventional for this type of machine. Roll 23 is hollow and mounted over shaft 20 on rollers 27, 28, 29 and 31, which are in turn mounted on cradle 30. In Fig. 2 one each of rolls 27, 28 and 29 are shown which are positioned at the left hand end of roll 23. There are three additional rolls located at the right hand end similarly to 27, 28 and 29 the middle one of which, namely 31, is shown in Fig. 1. Cradle 30 is supported thru shaft 32 by air pressure in cylinder 33 so that as roll 21 descends the end of shell 38 is held firmly between rolls 22 and 23 thereby preventing wrinkles forming as the shell is spun or closed in.

Shaft 19 is driven by a source of power and thru a mechanism not shown but which is conventional for the type of machine shown. Shaft 19 is mounted in a bracket so that its axis is parallel to that of shell 38. This bracket is preferably hinged on an extension of the frame of the machine to move toward and away from shaft 20 in a rocking motion, or slidably mounted to move radially relatively to shell 38 by a mechanism as explained in the preceding paragraph. Shaft 20 is mounted in the frame of the machine with the axis thereof disposed parallel to the axes of shell 38 and shaft 19 and is driven by a source of power not shown. Shaft 20 rotates in a direction opposite to that of shaft 19 and preferably at the same speed.

It is thus apparent that the shell 38 is caused to rotate about its axis during the interval that roll 21 is in contact with the open end portion of the shell.

Gear 25 is integral with roll 23 and is driven thru idler gear 26 and gear 24 which latter gear is mounted on shaft 20 and rotates therewith. This provides a positive drive for roll 23 as the gears stay in mesh as roll 23 moves up and down during the rolling operation.

Cradle 30 is guided by means of guide pins 36 and 37 and cap 43 prevents roll 23 from being unseated from rolls 27, 28, 29 and 31. It is to be noted that the drive thrust from gear 26 to gear 25 is downward and at an angle equal to the obliquity of the tooth angle as shown by line 42.

Bracket 34 to which bracket 35 is attached, which carries plate 39 and sleeve 41, is attached rigidly to the frame of the rolling machine. Bracket 35 is made separate from 34 for ease in set up and changing rolls.

Before the rolling-in operation starts the shell 38 having been previously drawn or built up by welding is substantially as shown in Fig. 5. The open end may or may not be trimmed as shown but in the case of the drawn shell the flared flange

facilitates rolling and conserves material. The operation of rolling in the open end of shell 38 proceeds as follows: Shell 38, as shown in Fig. 5, is placed in position, pusher plate 40 having been moved away and shaft 19 and roll 21 being raised to the position shown dotted. Pusher plate 40 is then returned to clamping position and roll 21 moves downward and contacts shell 38. The roll 23 is held firmly and yieldingly by means of the air in cylinder 33, and moves downward with roll 21 during the closing-in stage of the operation. When the downward travel of roll 21 is completed it is at once returned to the up-position and pusher plate 40 moves away for unloading and ready for loading the next shell to be rolled in.

While a rolling machine with horizontal shafts is shown, the method is equally well adapted to rolling machines with vertical shafts. Further, roll 22 could be built to rotate with shaft 20 but the preferred construction is as shown.

Roll 21 can be made with a groove as in Fig. 6 to receive the outward flanged end of shell 38. This groove tends to prevent buckling of the flange during the rolling-in operation.

The scope of the invention is not limited to any details shown or described but includes such embodiments of the broad idea, as fall within the scope of the subjoined claims.

Having described my invention I claim:

1. In a metal working machine of the kind described for reducing the diameter of the open end portion of cylindrical metallic shells each having a closed bottom and an outwardly turned flange at the open end thereof, the combination comprising: means to hold a shell at the bottom portion against radial and axial movement, said means including an abutting member and an axial moving clamping member; a supporting roll adapted to contact the inside face of the shell; an annular roll adapted to contact the inside face of the shell from the open end thereof to a point adjacent to the supporting roll; a pressure device to urge the annular roll against the shell; guiding means to guide said annular roll to move radially relatively to the shell; a forming roll adapted to move radially with respect to the shell and to contact the outside face thereof and to co-act with the annular roll during a portion of said movement to hold the end portion of the shell firmly and to close in said portion about the face and one edge of the supporting roll; and means to rotate the supporting roll and the forming roll thereby rotating the shell during the interval said rolls are in contact with the shell; and means for moving the forming roll toward the annular roll to grip the shell therebetween and thereafter for moving the two said rolls radially in unison to reduce the diameter of the open end portion of the shell.

2. In a metal working machine of the kind described for reducing the diameter of the open end portion of cylindrical metallic shells having closed bottoms and outwardly turned flanges at the open ends thereof, the combination comprising: means to hold a shell at the bottom portion against radial and axial movement, said means including an abutting member and an axial moving clamping member; a supporting roll adapted to contact the inside face of the shell and to hold the same in alignment; an annular roll adapted to contact the inside face of the shell from the open end thereof to a point adjacent to the supporting roll; a pressure device to urge the annular roll against the shell; guiding means

to guide said annular roll to move radially relatively to the shell; a forming roll adapted to contact the outside face of the shell and to coact with the annular roll and the supporting roll to reduce the open end portion of the shell; means for rotating the supporting roll and the forming roll, the means for rotating the supporting roll including a rotatable shaft which carries such roll; means for rotating the annular roll about its axis, comprising a train of gears driven by said shaft; and means for moving the forming roll toward the annular roll to grip the shell therebetween and thereafter for moving the rolls radially in unison to reduce the diameter of the open end of the shell.

3. In a metal working machine of the kind described for reducing the diameter of the open end portion of cylindrical metallic shells each having a closed bottom and an outwardly turned flange at the open end thereof, the combination comprising: means to hold a shell at the bottom portion against radial and axial movement, said

means including an abutting member and an axial moving clamping member; a supporting roll adapted to contact the inside face of the shell and to hold the same in alignment; an annular roll adapted to contact the inside face of the shell from the open end thereof to a point adjacent to the supporting roll; a pressure device to urge the annular roll against the shell; guiding means to guide said annular roll to move radially relatively to the shell; a forming roll grooved to receive the outward turned flange of the shell, and to coact with the annular roll and the supporting roll to reduce the open end portion of said shell; means for rotating the supporting roll and the forming roll; and means for moving the forming roll toward the annular roll to grip the shell therebetween and thereafter for moving the two rolls radially in unison to reduce the diameter of the open end portion of the shell.
